UNITED STATES PATENT OFFICE.

DELFRID FRANCISCO BRADY, OF ALGIERS, LOUISIANA.

HYDRAULIC SHOCK ABSORBER.

Application filed February 10, 1928. Serial No. 253,388.

The object of this invention is to provide a hydraulic shock absorber of simple, durable, and compact construction, capable of being manufactured at moderate cost, having no springs or expensive machined parts, and which will, without necessity for adjustment, absorb light and heavy shocks and rebounds, being adapted to cushion the descent of the body when the automobile 5 springs compress and to retard the upward rebound of the springs.

My improvements obviate the necessity of careful machining and fine workmanship which is so necessary to hydraulic shock absorbers which have been practical and successful.

In my shock absorber the piston and cylinder principle, and the fluid metering principle are employed in an improved manner 20 and a novel combination, as will more fully appear hereinafter.

In the accompanying drawings:

Figure 1, is a side elevation showing the device in use;

Fig. 2, is a vertical section; and

Fig. 3, is a horizontal section on the line 3—3, Fig. 2.

The body 1 is of elongated, tank-like form, of a size depending on the car on which the 30 device is to be used.

Rising within the central portion of the body is a stationary piston 2 which is secured to the bottom of the body and is separated from the walls thereof. This piston, 35 while shown as being of general rectangular cross sectional shape, may be cylindrical.

Rising from, and secured to, the bottom of the body 1 are the metering cones 3 arranged on opposite sides of the piston 2 and extending to a height of about one-half 40 of that of the body.

Extending inwardly from the inner, opposite, walls of the body are ribs or guides 4 which run from the bottom to the top flange 5 thereof.

The movable part of the device comprises a cylinder 6 of the shape of the piston 2 and telescoping over the latter, and cushioning blades or wings 7 which preferably lie in the same plane with the bottom of the cylinder and are provided with circular openings 8 which are of a diameter slightly less than that of the cones 3.

The cylinder 6, while open at its bottom, 55 is closed at its top, and it is guided by the ribs or guides 4.

The top 9 has an opening 10 through which the cylinder 6 can play, said top being provided with a stuffing-box 11 through which the cylinder 6 is adapted to move. 60

The top 9 overlies the flange 5 and preferably has a depending flange encircling flange 5. A gasket or packing 13 is interposed between the flange 5 and the top 9 and suitable bolts or fastenings 14 are provided 65 for the purpose of securing the top to the body.

Depending from the top 9 are cones 15 which are in vertical alinement with the cones 3 and are of the same dimensions as 70 cones 3. Being spaced apart the same distance as are the cones 3, the cones 15 are arranged with their vertical axes coinciding with the vertical axes of said cones 3 and they are arranged so that the openings 8 75 will receive said cones 15 when the cylinder 6 and the vanes or blades 7 rise above the apices of the cones 3.

The apices of the cones 3 are preferably slightly separated from the apices of the 80 cones 15. The sets of cones constitute, in connection with the holes 8, metering devices which permit the flow of the liquid through the holes 8, in one direction or the other, according to the up and down movements 85 of the cylinder 6 and the blades 7. It will be understood, that the flow of the liquid and the resistance offered to the travel of the blades and piston are proportional to the extent of travel of said piston and blades. 90 That is to say, when the piston and blades descend, the liquid beneath the blades exercises a constantly increasing resistance to their travel. Similarly, when the piston and blades rise, the same result occurs after 95 the blades reach a point of their ascent intermediate the apices of the cones.

Consequently, small irregularities of the road or pavement travelled over are readily absorbed, without noticeable effect because, 100 with the blades 7 in their normal position intermediate the apices of the cones, the liquid can easily pass through the holes 8. If the vehicle spring is compressed, instead of the body of the vehicle rapidly descending with 105 a jolt, it is gently cushioned, with a constantly increasing resistance offered to its descent. On the other hand, the unpleasant rebound action of vehicle springs is overcome because, as the piston and blades 110 ascend, the upper cones 15 gradually check the ascent of the piston and blades.

Any suitable means may be provided for connecting the body 1 to the axle and any suitable means for connecting the piston rod to the spring, the means shown being illustrative.

Any suitable oil or liquid may be used in the body 1. A suitable oil hole 16 is provided in the cover 9 through which the body may be filled with liquid.

10 Any light oil which is non-freezable and non-corrosive, may be used.

The sizes and relative proportions of the parts, such as the cones 3, piston 2, cylinder 6, and blades 7, will vary according to the 15 automobile on which the shock absorber is used and the load to which it will be subjected.

What I claim is:

1. In a hydraulic shock absorber, the combination with a liquid container having sets of opposing cones, of a piston and cylinder located between the respective sets of cones, and blades or vanes movable in the liquid container and carried by the movable member of said piston and cylinder, said blades

having openings adapted to receive the cones.

2. In a hydraulic shock absorber, the combination with a liquid container having a fixed piston, of sets of opposing cones located within the container on opposite sides of the piston, a movable cylinder which receives the fixed piston, and blades or vanes projecting in opposite directions from said cylinder and located within the container, 35 said blades having openings adapted to receive the cones.

3. In a hydraulic shock absorber, the combination with a liquid container, of a pair of opposing cones located within said container, a piston and cylinder, one member of which is movable and the other member stationary, and an apertured blade or vane carried by the movable member aforesaid, and adapted to telescope over one or the other of said cones according to its direction of movement.

In testimony whereof I affix my signature.

DELFRED F. BRADY.
